UNITED STATES PATENT OFFICE

WALTER P. OSGOOD, OF MELDEN, MASSACHUSETTS, ASSIGNOR TO BOSTON MACHINE WORKS COMPANY, OF LYNN, MASSACHUSETTS, A CORPORATION OF MASSACHUSETTS

FORMING BACK SEAMS

Application filed July 30, 1930. Serial No. 471,665.

The present invention relates to the manufacture of shoes, and more particularly both to a method of forming back seams in the quarter sections of shoe uppers and to a back seam pressing machine.

In order to join the quarters of a shoe upper it is customary to superimpose them, flesh faces exposed, with their curved edges aligned and then secure them together by through and through stitches. When the joined quarters are turned right side out for incorporation in a shoe, a ridge, comprising the material of the quarters between the adjacent free edges thereof and the seam, projects laterally inside the joined quarters. In order to reduce the abrupt character of the ridge it is subjected to an operation in which the ridge is pressed and/or covered with tape. Usually this operation is performed in a machine in which the ridge is subjected to pressure momentarily by a tool which also acts to feed the ridge in a step-by-step manner through the machine. Experience has demonstrated that it is impossible to press the ridge flat through its subjection to pressure momentarily and progressively applied. In consequence when the quarters are assembled with a counter the projecting ridge engages the back face of the counter and forms wind-puffs or air pockets between the counter and the quarters at opposite sides of the back seam. Stated in another way, the ridge holds the quarters away from the counter adjacent the back seam and thus prevents the cement used to paste the quarters to the counter, from securing the quarters adjacent the back seam to the counter. The ridge is thus free to shift on the counter during the pulling-over and bed lasting operations resulting in a crooked or distorted back seam. This freedom of the back seam to shift under strain is the reason why it is necessary to drive a tack through the quarters, counter and lining into the back face of the last, a practice which results in disfigurement of the finished shoe. Moreover the ridge by pressing against the counter tends to open further the opened quarters and thus to throw the thread in the back seam outwardly so that it is exposed to wear.

The principal objects of the present invention are to devise a method of forming shoe upper back seams whereby the back seam may be reduced to the thickness substantially of one of the shoe quarter sections and to produce a back seam pressing machine for practicing the back seam pressing step in said method.

To the accomplishment of these objects the various features of the present invention consist in certain methods, combinations, and arrangements of parts hereinafter described, and then pointed out broadly and in detail in the appended claims, possessing advantages readily apparent to those skilled in the art.

The various features of the present invention will be readily understood from an inspection of the accompanying drawings illustrating the best form of the invention at present known to the inventor, in which,

Figure 1 is a view in left side elevation of a seam pressing machine;

Fig. 2 is a view in front elevation of the seam pressing machine;

Fig. 3 is a view in sectional elevation on the line 3—3, of Fig. 4;

Fig. 4 is a view in front sectional elevation of the cooperating anvil and pressing jaws;

Fig. 5 is a view in perspective of the shoe quarter sections sewed together with the flesh side out by a curved seam, and

Fig. 6 is a view in perspective of the sewed quarter sections which have been separated slightly preparatory to the insertion of the sections into the seam pressing machine.

Referring to the drawings the quarters 7 and 8 are sewed together by a seam 9 with their wrong or flesh faces exposed, (Fig. 5). The quarters 7 and 8 are sewed together along a curved line to give a rounded contour to the quarters adjacent to the seam 9 when the quarters are turned right side out. The curve of the sewing line is predetermined so that the rounded contour imparted to the quarters will closely approximate the contour imparted to the counter which in turn approximates the contour of the heel end of the last upon which the shoe, embodying the quarters and the counter, is to be made. As

shown in Fig. 6 the material of the quarters between the free ends thereof and the seam 9 forms a ridge 10.

In order to subject both sections of the ridge 10 along the entire length of the seam 9 to pressure applied coincidentally, the joined quarters are separated slightly, without turning them right side out, and positioned on an anvil jaw 11 which is mounted like the anvil jaw in the seam pressing machine disclosed in my Patent No. 1,881,414, October 4, 1932.

The work supporting face of the anvil jaw 11 is convex laterally (Fig. 4) and longitudinally (Fig. 3) and engages the right side of the joined quarters which is the side exposed to view in the finished shoe. The ridge 10 is positioned in a vertical plane intersecting the longitudinal median line of the anvil jaw 11.

In order to flatten the upstanding ridge 10 and mold the quarters adjacent the back seam, the machine is provided with a pressing jaw 12 having a concave work engaging face complementary to the work engaging face on the anvil jaw 11. The jaw 12 is carried by a head 13 pivoted at 14 (Fig. 1) on the machine frame. The head 13 is oscillated to move the pressing jaw 12 from a position of clearance to a position of pressure and back to a position of clearance through a toggle mechanism 15 constructed to cause the pressing jaw 12 to dwell in its positions of clearance and pressure in a manner disclosed in my patent hereinbefore referred to during the continued operation of the shaft 16 from which the toggle mechanism 15 is actuated. The anvil jaw 11 and the pressing jaw 12 are heated in the same manner as the corresponding jaws disclosed in my patent hereinbefore identified.

As shown in Fig. 2 the machine is provided with two anvil jaws 11, two pressing jaws 12, and two oscillating heads 13. The heads 13 are swung forwardly and backwardly by their respective toggle mechanisms automatically and continuously to bring one pair of anvil and pressing jaws into a position of pressure and the other pair of anvil and pressing jaws into a position of clearance.

The heads 13 are held stationary when the jaws are brought into their positions of pressure and clearance as described in detail in my Patent No. 1,881,414. During the position of clearance the operative inserts the quarters joined by the back seam between the separated jaws. During the position of pressure the upstanding ridge of the back seam 9 is flattened under the combined action of heat and heavy pressure so that the quarters adjacent the back seam are consolidated into a unit uniform in thickness throughout its extent. The cooperating pair of anvil and pressing jaws are held in the position of pressure for a definite period of time to allow the back seam and the quarters adjacent

thereto to become set in the shape to which they are pressed and molded.

When the molded quarters are removed from the machine they are turned right side out and assembled with a counter. Without the ridge the quarters may be cemented to the counter with no cavities therebetween adjacent the back seam. This permits a strong union between the quarters and the counter which prevents distortion of the back seam under pulling-over or bed lasting strains and obviates the use of a back seam tack.

In the appended claims the term "shoe quarter sections" has been used to designate quarters or linings therefor or for the counter of the shoe.

What is claimed as new, is:

1. That improvement in the art of forming back seams for shoes which consists in sewing a pair of shoe quarter sections together along a curved line, separating the pieces to present a seam ridge on one face of the work and a seam crease on the other face of the work, supporting the seam crease face of the work on a curved surface and subjecting the seam ridge to sufficiently heavy pressure applied along its entire length coincidentally to reduce the seam ridge to the thickness substantially of one of the shoe quarter sections.

2. In a seam reducing machine, the combination with a jaw for supporting work having a concavo-convex formation comprising the quarter sections to form the heel portion of a shoe upper seamed together by a seam presenting a seam ridge on one face of the work and a seam crease on the other face of the work, said jaw directly engaging the seam crease face of the work, and a cooperating jaw acting directly on the seam ridge, of means for closing said jaws with heavy pressure to reduce the seam ridge to the thickness substantially of one of the shoe quarter sections.

In testimony whereof I have signed my name to this specification.

WALTER P. OSGOOD.
